Patented Feb. 28, 1928.

UNITED STATES PATENT OFFICE.

LAWRENCE G. REPELL, OF KANSAS CITY, MISSOURI.

AUTOMATIC CENTERING INSTRUMENT.

Application filed June 25, 1927. Serial No. 201,472.

My invention relates to improvements in automatic centering instruments. It relates particularly to dividers provided with automatic centering means.

One of the objects of my invention is to provide an instrument of the kind described with which the center between two points may be easily, automatically and quickly determined.

A further object of my invention is to provide an instrument of novel construction with which the distance between two points may be easily and quickly determined and indicated.

Still another object of my invention is to provide an instrument of the kind described, which is simple, cheap, durable, not likely to get out of order, which is easily and quickly operated, which is reliable in its operation, and which, when not in use can be disposed in compact form.

The novel features of my invention are hereinafter fully described and claimed.

In the accompanying drawing, which illustrates the preferred embodiment of my invention,

Fig. 1 is a plan view of my improved instrument shown in an operative position, the nut being partly broken away.

Fig. 2 is an end elevation of the same.

Fig. 3 is an enlarged section on the line 3—3 of Fig. 1.

Fig. 4 is an enlarged section on the line 4—4 of Fig. 1.

Fig. 5 is a plan view of what is shown in Fig. 3, the nut being removed.

Similar reference characters designate similar parts in the different views.

My improved instrument is provided with two arms 1 and 2, which are pivoted, adjacent to one set of their ends, by a pin 3 to a guide member 4, adjacent to one end thereof.

Said guide member 4 may be a flat bar on which is longitudinally adjustably mounted

a marker, comprising, preferably a pin 5 which extends through and has a squared portion 6 slidably mounted in a longitudinal slot 7 with which the guide member 4 may be provided. One end of the pin 5 has a pointed head 8 with which indentations or marks may be made.

The other end of the pin 5 is threaded and has fitted removably on it a clamping nut 9 adapted to bear against the guide member 4 for holding the pin 5 in the position to which it may be adjusted.

There may be slidably mounted on the guide member 4 an indicating plate 10 through which the pin 5 extends. The plate 10 may be provided at opposite ends with inwardly turned pointed lips 11 and 12, Fig. 5, which align transversely with the axial center of the pin 5, and which are adapted to overlap the adjacent side of the guide member 4 and to respectively indicate the graduations 13 and 14 which may be provided on the adjacent side of the guide member 4 at opposite sides respectively of the slot 7, Figs. 1 and 5.

Two links 15 and 16 have one set of their ends pivoted to the pin 5 between the plate 10 and the head 8 of the pin 5. The links 15 and 16 are respectively pivoted by pins 17 and 18 to the arms 1 and 2 at equal distances, preferably, from the pin 5 and from the pin 3.

The ends of the arms 1 and 2 distant from the pin 3 are provided respectively with pointed indicating devices 19 and 20 extending respectively at angles to the bodies of the arms 1 and 2.

The graduations 13 respectively represent distances from either indicating pointer 19 or 20 to the point of the head 8 of the pin 5 in different positions of the arms 1 and 2.

The graduations 14 represent actual distances or measurements taken from the end of the guide member 4, distant from the pin 3, to the point of the head 8.

In using the device to find the center between two points, set the pointers 19 and 20 at the two points, and the links 15 and 16 will slide the pin 5 in the slot 7 to a position equi-distant from the pointers 19 and 20 and the two points. By pressing against the nut 9 or the upper end of the pin 5, the point of the head 8 will make a mark, which is centrally between the two points.

The lip 11 will indicate on the graduations 13 the distance between the point of the head 8 and either of the two points.

Thus the middle of a board may be readily determined by setting the pointers 19 and 20 of the arms 1 and 2 at the edges of the board, and the point of the head 8 of the pin 5 will be in the exact center of the board.

The indicating lip 12 will indicate on the graduations 14 the distance the point of the head 8 from the end of the guide member 4 distant from the pin 3. By having the indicating pointers 19 and 20 extending re-

spectively at angles to the bodies of the arms 1 and 2, said pointers may be made to become engaged with and easily held with one hand against opposite edges of a board, 5 so that the other hand of the operator will be free to operate the marker pin 5.

I do not limit my invention to the structure shown and described, as many modifications, within the scope of the appended 10 claims, may be made without departing from the spirit of my invention.

What I claim is:—

1. In an instrument of the kind described, a graduated guide member, a marker movable thereon and arranged to register with the graduations on said guide member, an arm pivoted to said member and having an indicating device, and a link pivoted to said arm and to said marker, said graduations 15 representing respectively different distances corresponding to different distances between said device and said marker, when said arm is swung to different positions with respect to the said member.
2. In an instrument of the kind described, a graduated guide member, a marker movable thereon and arranged to register with the graduations on said guide member, two arms pivoted to said member and having 20 each an indicating device, and two links pivoted to said marker and respectively pivoted to said arms, said graduations representing

different distances between said marker and either of said devices, when said arms are swung to different positions with respect to 35 said member.

3. In an instrument of the kind described, a guide member, a marker movable thereon and arranged to register with the graduations on said guide member, two arms pivoted to said member and having extending 40 respectively therefrom at like sides and in like directions parallel with the axis of said arms two indicating pointers, and two links pivoted to said marker and respectively 45 pivoted to said arms.

4. In an instrument of the kind described, a guide member having a row of graduations, a marker movable on said guide member and co-operating with said graduations, 50 two arms pivoted to said member and having extending respectively therefrom at like sides and in like directions parallel with the axis of said arms two indicating pointers, and two links pivoted to said marker and 55 respectively pivoted to said arms, said graduations representing different distances between said marker and either of said indicating pointers, when said arms are swung to different positions with respect to said 60 member.

In testimony whereof I have signed my name to this specification.

LAWRENCE G. REPELL.
